UNITED STATES PATENT OFFICE.

WILLIAM BUTTLER, OF REDKEY, INDIANA.

APPARATUS FOR FIRE-FINISHING GLASSWARE.

SPECIFICATION forming part of Letters Patent No. 617,920, dated January 17, 1899.

Application filed April 16, 1897. Serial No. 632,478. (No model.)

To all whom it may concern:

Be it known that I, WILLIAM BUTTLER, of Redkey, in the county of Jay and State of Indiana, have invented a new and useful Improvement in Apparatus for Fire-Finishing Glassware, of which the following is a full, clear, and exact description, reference being had to the accompanying drawings, forming part of this specification, in which—

10 Figure 1 is a sectional side elevation showing my improved fire-finishing apparatus, and Fig. 2 is an enlarged cross-sectional view on the line II II of Fig. 1.

15 The object of my invention is to provide means for the rapid fire-finishing of the ends of glass articles.

20 I have especially constructed my apparatus for fire-finishing the ends of lamp-chimneys which have been cracked off from blanks or other articles in conjunction with which they have been blown; but within the scope of my broad claims the apparatus is capable of use with other kinds of glass articles.

25 The apparatus comprises a furnace-chamber having an elongated opening at the top, together with an overhead carrier by which the articles are carried in a vertical position, with the ends to be finished directed toward and into the opening, so that as the articles 30 pass along their edges are heated and finished in the desired manner.

The invention also consists in certain other items hereinafter recited in the claims.

35 In the drawings, 2 represents a furnace closed at the sides and bottom and having at the top an elongated opening 3.

40 4 are gas-burners so arranged as to heat the end portion 5 of the furnace more highly than the other end, and under that part of the elongated opening to which the glass articles first come there is an arch or plate 6, of asbestos, which protects the articles from the direct heat of the flame and causes them to be heated at that place only by radiated heat, 45 thus rendering the heating action more gradual than it otherwise would be.

The carrier for the glass chimneys consists of an endless chain 7, passing over sprocket-wheels 8 and extending to the furnace preferably from the cracking-off apparatus at which the end of the glass article to be fire-finished is separated from the blank or article with

which it is formed. The lower branch of the chain extends over and in proximity to the elongated opening, and the links are provided at intervals with downwardly-extending forked supports 9, adapted to receive the necks of the chimneys. The lower branch of the endless chain is supported in horizontal position by horizontal bars 10, which extend laterally from the chain and travel on fixed supporting-guides 11. As the lamp-chimneys are cracked off they are placed within the supports on the lower branch of the chain and are carried thereby in vertical position to the elongated opening of the furnace. At the place where the end of the lamp-chimneys first comes opposite to this opening the latter is covered by the plate or arch 6, so that the end of the chimney is heated only by radiation; but when the chimney passes the same and reaches the open or uncovered part of the opening it is subjected to the direct action of the flame and is more rapidly heated. The heat which it meets increases as the chimney approaches the end of the furnace until finally its end is sufficiently heated and softened to remove the sharp or wire edge from its end, which it is the purpose of the finishing operation to efface. The endless chain extends some distance beyond the end of the furnace—say about six inches, more or less—so that after the chimney has passed the end of the furnace-opening a sufficient time elapses before its removal to permit it to cool somewhat. At the point where the chain passes around its second sprocket-wheel 8 the chimneys will drop of themselves from the forked supports into a chute 12, down which they roll into a box. (Not shown.) To prevent the chimneys from breaking, series of strings of asbestos or other yielding material 13 are hung in the box, so that as the chimney rolls thereinto some of the asbestos threads will always be interposed between it and the next chimney and will afford a cushion to prevent sudden jar and breaking of the glass.

The advantages of my invention will be appreciated by those skilled in the art. It enables the work of fire-finishing to be carried on very largely automatically, much labor is saved, and the work is performed far more rapidly and with less liability of breakage.

than in hand-finishing at the ordinary glory-hole furnace or in the use of prior apparatus and furnaces heretofore devised for like purposes.

5 The holding of the glass articles with the end to be fire-finished or glazed directed downwardly toward the source of heat affords important advantages. The end of the glass article is not apt to be distorted when 10 heated in this position, and, moreover, the tendency of the heated currents of air to rise causes them to flow upwardly and to envelop the entire body of the article, thus partially annealing the same and preventing the very 15 considerable breakage of glass which results when the chimneys are presented laterally to the source of heat or upwardly from below the same. In the latter cases only the end of the chimney is heated, and as the body of the 20 chimney remains entirely cool the unequal expansion which results is apt to break the glass.

My improved apparatus is useful not only for heating chimneys, but for heating and 25 finishing other articles. Articles may be heated by my apparatus either for the simple purpose of glazing them or to soften them to be finished in molds or by hand-tools.

Within the scope of my invention as defined 30 in the claims the apparatus may be modified in various particulars, since

What I claim is—

1. In apparatus for finishing glassware, a furnace having a slot in its top forming an 35 opening, and a carrier above the opening and external to the furnace, said carrier having holders exterior to the furnace and arranged to hold the glass articles in a vertical position partly within and partly without the slot and 40 expose the lower portions to the heat of the furnace passing through the opening.

2. In apparatus for finishing glassware, a furnace having an elongated opening through the top of the furnace, a horizontally-moving 45 endless carrier above and external to the furnace, and exterior holders on the carrier arranged to support the articles in a vertical position partly within and partly without the opening.

50 3. The combination with a furnace having an elongated opening through its top, of an

endless carrier having holders exterior to the furnace and arranged to expose the articles to the heat from the opening, and means for intensifying the heat at the delivery end of 55 the opening.

4. The combination with a furnace having an upper elongated opening, of a heat-radiating plate arranged to shield the portion of the opening first entered by the articles to be 60 finished.

5. In apparatus for finishing glassware, the combination with a heating-furnace having an elongated opening through its top, of an external endless chain above the opening 65 having holders exterior to the opening arranged to support the glass articles in a vertical position and carry their lower portions through the opening, and means for continuously moving said chain.

6. In apparatus for finishing glassware, the combination with a furnace having an upper elongated opening, of a carrier extending from the cracking-off apparatus past the opening, holders upon the chain arranged to 75 support the glass articles in vertical position and carry their lower portions through the opening, and automatic mechanism for discharging the articles from the holders after the same have been heated.

7. In apparatus for finishing glassware, the combination with a furnace having a slot or opening through its top, of means for varying the heat in different portions of the opening, and an upper external carrier having 85 holders exterior to the slot or opening and arranged to support the glass articles in vertical position partly within and partly without the slot and carry them through the opening.

8. The combination with an endless chain, 90 of a chute at the end thereof down which the glass articles when released travel, a receptacle for the glass articles, and hanging flexible cushions arranged in series so as to separate the glass articles and prevent their hitting against one another.

In testimony whereof I have hereunto set my hand.

WILLIAM BUTTLER.
